W. C. BOWLEN
PRECIOUS METAL WARE
Filed Nov. 3, 1923

BY

Frank A. Cutler, ATTORNEY.

UNITED STATES PATENT OFFICE.

WILLIAM C. BOWLEN, OF HOLYOKE, MASSACHUSETTS.

PRECIOUS-METAL WARE.

Application filed November 3, 1923. Serial No. 672,677.

To all whom it may concern:

Be it known that I, WILLIAM C. BOWLEN, a citizen of the United States of America, and a resident of Holyoke, in the county of 5 Hampden and State of Massachusetts, have invented certain new and useful Improvements in Precious-Metal Ware, of which the following is a specification.

My invention relates to improvements in 10 candlesticks, vases, and other articles or objects which, by reason of their height or otherwise, need weighting or stabilizing in order to prevent them from being overturned easily, and resides in providing such 15 a candlestick, vase, or other article or object with a removable weight, plug, or stabilizer, the same usually being located in the lower portion or base of such object, all as herein-after set forth.

20 As is well understood, it is customary to weight the lower parts or bases of candlesticks, vases, and other more or less similar articles or objects, the material used for that purpose, in precious metal ware, such as 25 ware made of gold or silver, being a base metal or something of little or no intrinsic value, a mixture of sand and paraffin frequently being employed. This base metal or material is permanently built into or sealed 30 within the object, hence it is impossible, or in any event impracticable, to separate from the precious metal the stabilizing element, for the purpose of determining the exact 35 weight and value of the former, or for any other purpose, without destroying such object. The primary object of my invention, therefore, is to produce a precious metal ware article which is a complete and separate entity, and to provide such article with 40 a removable member of base material for stabilizing purposes. It will be seen, then, that the base material can be separated from the previous metal, leaving the latter in condition to be weighted and valued with absolute 45 certainty.

Another object is to provide for a precious metal ware article a base material stabilizer which not only can be connected with and removed from said article at will, but is comparatively simple and inexpensive, convenient, and in no way detracts from the value and appearance of said article.

50 A further object is to afford, in an article of the character described, simple and convenient engaging and releasing means,

whereby the base material stabilizer can be connected with and secured to the precious metal ware article, and disengaged and removed therefrom.

Other objects and advantages will appear 60 in the course of the following description.

I attain the objects and secure the advantages of my invention by the means illustrated in the accompanying drawings, in 65 which—

Figure 1 is a central, vertical section through a candlestick in which is embodied a practical form of my invention; Fig. 2, a bottom plan of said candlestick, and, Fig. 3, a side elevation of the stabilizer.

70 Similar reference characters designate similar parts throughout the several views.

In the drawings, a candlestick is represented at 1, and a weight, plug, or stabilizer at 2. It is assumed that the candlestick 1 is 75 made of gold or silver, while the stabilizer 2 is made of lead or other base metal, material, or materials, it being obvious that the stabilizer, in order to have practical utility, must be made of a material or materials of 80 less intrinsic value than that of which the candlestick is constructed.

The candlestick 1 has a hollow base 3, and in the present example is hollow throughout its entire length. Inside of the base 3, integral therewith, and somewhat remote from or above the plane of the bottom edge thereof is an annular member 4 provided with a horizontal, annular flange 5 and one or more, horizontal, arcuate lugs or lips 6. 85 The lips 6 are formed from inner edge portions of a flat, horizontal ring 7 which is integral with the member 4. Rising from the ring 7 is an annulus 8 at the top of which is the flange 5, said flange extending inwardly from said annulus. There are here present two lips 6, and they are oppositely disposed and extend inwardly from the junction of the annulus 8 with the ring 7, beneath the flange 5. An annular groove is 90 formed by the annulus 8 and the flange 5 and lips 6, which groove opens downwardly between said lips. What may be termed the interior diameter of the lips 6 is less than that of the flange 5 in this case.

100 The weighted plug or stabilizer 2, which, as hereinbefore stated or intimated, may be made of any suitable base material or materials and in any suitable manner, has a body which is adapted to pass through the flange 105

5, the lower portion of said body here being cylindrical as represented at 9. Surrounding the base or cylindrical part 9 of the stabilizer 2 is a flange 10, although such 5 flange is not an absolutely necessary part of the invention, and preferably said stabilizer is provided on the bottom with a handle 11. Formed on the cylindrical part 9, immediately above the flange 10, is one or more 10 arcuate flanges 12. There are here two oppositely-disposed flanges 12 and they project beyond both the cylindrical part 9 and the flange 10. The diameter of the cylindrical part 9 is approximately equal to the 15 interior diameter of the flange 5, what may be termed the outer diameter of the flanges 12 is approximately equal to the interior diameter of the annulus 8, and the outer diameter of the flange 10 is approximately 20 equal to the inner diameter of the lips 6, while the thickness of said first-named flanges is approximately equal to the distance between said first-named flange and said lips. 25 The flanges 12 are separated by sufficient distance to receive between the ends thereof the lips 6, and said lips are separated a sufficient distance to receive between their ends said flanges. 30 In practice, the stabilizer 2 is thrust upwardly in the base of the candlestick through the flange 5, partially rotated to enable the lips 6 to pass between the flanges 12 and said flanges to pass between said lips, 35 elevated or thrust still further into said base until said flanges 12 contact with said flange 5, and partially rotated in either direction to engage said flanges 12 with said lips above the latter, the handle 11 being mean- 40 while grasped to facilitate these operations. The stabilizer is thus held securely in place in the candlestick, and to all intents and purposes becomes a part of the same. The stabilizer, after being placed in position in 45 the manner just explained, furnishes the necessary weight in the bottom of the candlestick to prevent in great measure the accidental upsetting, or the too easy overturning, of said candlestick. 50 To remove the stabilizer 2 from the candlestick 1, it is simply necessary to grasp the handle 11, partially rotate said stabilizer to unlock or disengage the flanges 12 from the lips 6, and withdraw said stabilizer entirely from the base 3. 55 It is not necessary, as hereinbefore intimated, that the number of the lips 6 and the number of the flanges 12 be in each case limited to two. 60 Although I have illustrated my invention in connection with a candlestick, it is to be understood that it is equally applicable to numerous articles or objects that may be described as tall and slender, and for which 65 reason and because they are so light in

weight or on some other account stand in need of a stabilizing element in the lower part thereof.

Changes in the shape, size, construction, and arrangement of some or all of the parts 70 of the combined object and stabilizer, in addition to those hereinbefore specifically pointed out, may be made without departing from the spirit of my invention or exceeding the scope of what is claimed. 75

What I claim as my invention, and desire to secure by Letters Patent, is—

1. In precious metal ware, a precious metal ware object, a normally fixed base material stabilizer, and means to attach said stabilizer to and detach it from said object on the inside, whereby, when said stabilizer is detached from said object, the value of the object can be determined by weight. 80

2. In precious metal ware, a precious metal ware object, a normally fixed base material stabilizer, and means to attach said stabilizer to and detach it from the inside of the base of such object, whereby, when said stabilizer is detached from said object, 90 the value of the object can be determined by weight. 95

3. In precious metal ware, a precious metal ware object, a normally fixed base material stabilizer concealed in said object, 100 and interior and exterior engaging means with which said object and stabilizer are respectively provided whereby the latter may be engaged with and disengaged from the former, the construction and arrangement of parts being such that, when said stabilizer is detached from said object, the value of the object can be determined by weight. 105

4. As an improved article of manufacture, 105 an object, of the class described, which object is complete in itself, and a normally fixed stabilizer wholly within and distributed equally on all sides of the axis of said object, said object and stabilizer having 110 means whereby the latter may be engaged with and disengaged from the former by rotating either or both.

5. As an improved article of manufacture, 115 an object, of the class described, hollow in the lower portion and provided inside, intermediate of the axis of said object and the periphery of said lower portion, with engaging members through which is an opening, and a stabilizer receivable in said opening 120 and provided with engaging members to cooperate with said first-named engaging members to retain said stabilizer in place.

6. The combination, in precious metal ware, with an object having its lower portion hollow and provided with a flange above and a lip below, of a stabilizer provided with a flange adapted to engage said first-named flange when said stabilizer is inserted in said hollow portion and to be 125 130

engaged with and disengaged from said lip.

7. The combination, in precious metal ware, with an object having its lower portion hollow and provided with a flange above and lips below, of a stabilizer provided with flanges adapted to engage said first-named flange when said stabilizer is

inserted in said hollow portion, and to be engaged with and disengaged from said lips, said stabilizer flanges and said lips being so proportioned as to permit them to pass each other when the stabilizer is positioned for that purpose.

WILLIAM C. BOWLEN.
